(57) **CLAIM**

The ornamental design for a portable power source, as shown and described.

DESCRIPTION

FIG. 1 is a front elevational view of a portable power source showing our new design;

FIG. 2 is a rear elevational view thereof;

FIG. 3 is a left side view thereof;

FIG. 4 is a right side view thereof;

FIG. 5 is a top plan view thereof;

(Continued)

FIG. 6 is a bottom plan view thereof;
FIG. 7 is a first perspective view thereof; and,
FIG. 8 is a second perspective view thereof.
